(57) **CLAIM**

The ornamental design for a single space parking meter, as shown and described.

DESCRIPTION

FIG. 1 is a top front left perspective view of a single space parking meter showing the new design;

FIG. 2 is a top back left perspective view thereof;

FIG. 3 is a left side elevation view thereof;

FIG. 4 is a front elevation view thereof;

FIG. 5 is a right side elevation view thereof;

FIG. 6 is a back elevation view thereof; and,

FIG. 7 is a top plan view thereof.

The broken lines are for environmental purposes only and form no part of the claimed design.
